COVERED COAT HANGER

Irma S. Walsh, Washington, D. C.

Application July 1, 1957, Serial No. 46,781

Term of patent 7 years

(Cl. D80—8)

Fig. 1 is a side elevational view of a covered coat hanger embodying my new design, the other side being substantially the same and the knitting being schematically shown; and

Fig. 2 is an enlarged sectional view on line 2—2 of Fig. 1.

The characteristic features of my design for the covered coat hanger disclosed, reside in having bands of knitting with the wales of each band alternating in direction as shown and the end bands being of a darker shade or color than the balance of the cover portion.

I claim:

The ornamental design for a covered coat hanger, as shown and described.
